His Attorney.

UNITED STATES PATENT OFFICE.

HERMANN LEMP, OF ERIE, PENNSYLVANIA, ASSIGNOR TO GENERAL ELECTRIC COMPANY, A CORPORATION OF NEW YORK.

ELECTRICALLY-OPERATED FUEL-VALVE.

1,323,778.

Specification of Letters Patent.

Patented Dec. 2, 1919.

Application filed March 2, 1918. Serial No. 220,051.

To all whom it may concern:

Be it known that I, HERMANN LEMP, a citizen of the United States, residing at Erie, in the county of Erie, State of Pennsylvania,

5 have invented certain new and useful Improvements in Electrically-Operated Fuel-Valves, of which the following is a specification.

This application is a continuation in part 10 of my application, Serial No. 31,376; filed June 1, 1915.

The present invention relates to fuel injectors for use particularly for controlling the admission of fuel to internal combustion engines of the high compression type. As is well understood, in operation fuel is delivered to these injectors in measured quantities by a suitable pump, after which the needle valve of the injector is opened and 15 the charge of fuel is blown into the engine cylinder against the pressure therein by means of compressed air, generally termed the blast air. In ordinary practice this blast air has a pressure of from 800 to 1000 20 lbs. per square inch.

In injectors as heretofore constructed, the stem of the needle valve projects through the casing and is operated by means of a suitable lever or other device from the crank 30 shaft or other part of the engine. The interior of the valve casing is subjected to the pressure of the blast air and to prevent leakage around the valve stem a suitable stuffing box is provided for the stem. As 35 will be evident, such a stuffing box must be maintained air tight up to about 1000 lbs. per square inch pressure and this has proven very difficult owing to the rapidity with which the stem moves, and the fact that it is soon corroded more or less by gases which 40 may be formed, for example, by sulfur from the fuel uniting with the air and moisture present to form sulfuric acid. These stuffing boxes are, therefore, a source of a good 45 deal of trouble, and the best of materials and great care, together with frequent repacking is required in order to keep the packing tight.

One object of the present invention is to 50 provide an improved structure wherein the stuffing box for the stem is entirely eliminated, the whole stem being inclosed within the fuel injector casing. To this end I dispense with the usual lever for mechanically 55 operating the needle valve and use in place

thereof an electromagnet which is preferably arranged within an extension of the injector casing and acts to operate the fuel valve magnetically.

A further object of my invention is to 60 provide an improved structure which will require the minimum amount of electrical energy for lifting the fuel valve from its seat whereby destructive sparking on the commutator devices used will be avoided. 65

A still further object of my invention is to 70 provide an arrangement in which the magnet and armature may be readily adjusted relative to each other so as to obtain an adjustment giving the desired magnetic pull.

For a consideration of what I believe to be novel and my invention, attention is directed to the accompanying specification and the claims appended thereto. 75

In the accompanying drawing, Figure 1 is a longitudinal sectional view of my improved fuel injector; Fig. 2 is a section taken on line 2-2, Fig. 1, and Fig. 3 is a diagram of connections of an arrangement 80 for operating the valve.

Referring to the drawing, 4 indicates a wall of the cylinder of a high compression internal combustion engine, and 5 the cooling jacket. 6 indicates a column which 85 crosses the cooling space and is provided with a counter-bored opening into which is seated pressure tight the casing 7 of the fuel injector. 8 indicates the needle valve of the injector, 9 the seat therefor, and 10 the 90 flame plate. Fuel is admitted to the injector by way of conduits 11 and 12, and opening 13, and blast air by way of conduit 14. The specific structure of this portion of the injector forms no part of the present 95 invention and further description is, therefore unnecessary. It may be of any suitable or desired structure.

The casing 7 is provided with an extension 15 of somewhat larger diameter than itself 100 and preferably formed integral therewith. The extension is open at the outer end and over the opening is screwed a carrying member 16 threaded on the outer portion to receive a closing cap 17. The carrying member 16 has a threaded opening at its central portion into which is screwed an extension 18 on the end of the core 19 of an electromagnet, the winding of which is indicated 105 at 20. The extension 18 is held in place on 110

carrying member 16 by means of a lock nut 21. One end of winding 20 is grounded on the frame of the magnet and the other end extends through an opening 22 in extension 5 18 and is connected to a contact button 23 carried by an insulating bushing 24 which telescopes into a cylinder 25. The cylinder 25 is also shown as being made of insulating material and has an opening in one end 10 through which the extension 18 projects, the end of the cylinder resting against the lock nut 21. Between the cylinder 25 and the bushing 24 is a spring 26 which presses the contact button 23 against a contact 27. Contact 27 carries a post 28 which projects to the outside of cap 17 and is provided with suitable clamping nuts 29. The shell of the electromagnet is indicated at 30. The stem 15 of needle valve 8 has a curved head 31 which forms a part of the magnet armature and which fits into a counter-sunk opening 32 in an armature part 33. The head 31 is not flush with the surface of armature part 33 but terminates somewhat within the same, 20 and it is held in position in the opening 32 by means of a spring 34 which at one end engages the head 31 and at the other end the bottom of a hole in the core 19. Spring 34 also serves to hold valve 8 on its seat 9. 25 The armature part 31 is biased to a position away from the electromagnet by a suitable spring washer 35 made of insulating material, and its movement in such direction is limited by a suitable means, as the shoulders 35^a.

In Fig. 3 I have shown diagrammatically an electrical arrangement for periodically energizing the winding 20. The winding 20 has its one terminal connected by a conductor 36 to a brush 37 which engages the periphery of a disk 38 having a long section of insulating material 39 and a short section of contact material 40 on its periphery. The disk 38 is connected by a conductor 41 to a suitable battery or other source of electrical energy 42 which in turn is grounded as indicated at 43. In the conductor 41 is a suitable switch 44 by means of which the battery conduit may be closed and opened manually. 45 The other terminal of winding 20 is grounded as indicated at 45. As will be readily understood, when the brush rests on the insulating section 39 the electromagnet circuit will be open, while when passing over the contact segment 40 such circuit will be closed and the magnet energized to open the needle valve. When the electromagnet is energized it attracts both armature parts 33 and 31, 50 The two parts moving together until the armature part 33 strikes the face of the magnet, after which the head 31 alone moves farther toward the pole piece 19 to complete the opening of the valve 8. The head 31 forms in substance a part of the armature, as is obvious; that is, the armature is made up of 55

two concentric parts, one of which is connected directly to the valve 8 and can move the valve independently of the other part of the armature. The disk 38 will, of course, be suitably arranged to be turned in synchronization with the engine shaft, as, for example, by being mounted on the cam shaft of the engine. This is not shown in the drawing, however, being unnecessary for a complete disclosure and understanding of 70 my invention. 46 are plugs which may be removed from openings 47 in the wall 14 so that by looking through openings 47 the adjustment of the armature 33 relative to the electromagnet pole face may be observed. 75

In connection with the operation of fuel valves I have found that much more energy is required to pull the needle valve off its seat than is required to lift it further after it has once left its seat. In other words, 80 the greatest pull is required to start the needle valve into motion. In the operation of my invention, therefore, the armature part 23 is set up quite close to the face of the electromagnet so that its total movement 85 will represent only a fraction of the movement required to open the valve 8 the desired amount. This adjustment is effected by adjusting the magnet in the holder 16, the correct adjustment being observed by 90 looking through the openings 47. When in correct position, the magnet is locked thereby by the nut 21. With any adjustment the spring 26 always maintains contacts 23 and 25 in engagement. Since the armature part 100 33 is brought so close to the pole face of the electromagnet the amount of current necessary to give the required initial pull to start the valve 8 from its seat will be very much less than if it were spaced a distance. 105 from the pole face equal to the total valve movement. During this initial movement the armature part 33 and head 31 move together and the head is thus brought closer to the core 19 so that after the armature 110 part 33 strikes the pole face of the magnet the magnetization of core 19 will be sufficient to continue moving the head 31 to complete the movement of valve 8.

In accordance with the provisions of the 115 patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:—

1. In a fuel injector, the combination of a 125 casing, a fuel valve located therein which is biased to closed position and has no moving part which projects through the casing wall, an electromagnet also wholly inclosed within said casing, the armature of the mag- 130

net being operatively connected to the fuel valve, and means for adjusting the distance of the armature from the pole face of the magnet.

5. 2. In a fuel injector, the combination of a casing, a fuel valve therein, and an electromagnet for actuating it, said electromagnet having its armature formed in two parts one of which is connected directly to the 10 valve and is located farther from the pole face of the magnet than the other, both parts of said armature acting on the valve during its initial movement.

3. In a fuel injector, the combination of a 15 casing, a fuel valve therein, and an electromagnet for actuating it, said electromagnet having its armature formed in two parts one of which is connected directly to the valve and is located farther from the pole 20 face of the magnet than the other, both parts of said armature acting on the valve during its initial movement, and means for adjusting the armature and pole face of the magnet relative to each other.

4. In a fuel injector, the combination of a 25 casing, a fuel valve therein, and an electromagnet for actuating it, said electromagnet having its armature formed in two concentric parts, one of which is movable toward the pole face of the magnet independently 30 of the other and is spaced farther therefrom, and means connecting such one of the magnet parts to the fuel valve.

5. In a fuel injector, the combination of a 35 casing, a fuel valve located therein which is biased to closed position and has no moving part which projects through the casing wall, an electromagnet also wholly inclosed within said casing, the armature of said electromagnet being formed in two concentric 40 parts, one of which is movable toward the pole face of the magnet independently of the other and is spaced farther therefrom, and means connecting such one of the magnet parts to the fuel valve. 45

In witness whereof I have hereunto set my hand this 26th day of February, 1918.

HERMANN LEMP.
